ROTARY TAKE-UP FOR SEWING MACHINES

Raymond H. Van Wagener, Stamford, Russell Carmichael, Devon, and Frank Parry, Trumbull, Conn., assignors to The Singer Manufacturing Company, Elizabeth, N. J., a corporation of New Jersey

Application October 11, 1950, Serial No. 189,528

22 Claims. (Cl. 112—248)

1

This invention relates to sewing machines and more particularly to improved take-up devices for the needle thread of such machines.

The invention has for its primary object to provide a simple arrangement involving solely a single rotary element suitably formed and disposed to cooperate with adjacently positioned thread-guides to control the needle-thread of a sewing machine in a positive and effective manner during the complete stitch-forming cycle.

Another object of the present invention is to provide a rotary take-up mechanism for a lock-stitch sewing machine in which the rotary element thereof comprises solely a single member preferably formed as a stamping of sheet metal shaped and bent into appropriate form such that the action on the thread is gentle, resulting in substantially trouble-free operation.

A further object of the present invention is to provide a take-up mechanism of the character indicated wherein the component parts are judiciously formed and arranged so that the threading thereof is extremely simple and can be accomplished by merely sidewise introducing the thread through a suitable threading slot at the head-end of the sewing machine.

Another object of the present invention is to provide a rotary take-up mechanism for a lock-stitch machine in which the needle-thread is controlled by a single rotary element having a cam-shaped thread-engaging edge, the rotary element being mounted on an extension of the needle-bar actuating shaft.

Still another object of the present invention is to provide an improved needle-thread take-up mechanism in which the single moving thread-engaging member is shaped so that during normal thread handling the thread does not traverse a path intercepted by a suitable thread-severing means, but in the event of thread-breakage changes the path of the thread such that it is cut and thus prevented from being wound on the thread-engaging member.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 represents a vertical sectional view of a sewing machine embodying our invention.

2

Fig. 2 represents a left-end elevation of the sewing machine shown in Fig. 1.

Fig. 3 represents a front elevation of the head end-portion of the machine shown in Fig. 1.

Fig. 4 represents a vertical section taken longitudinally of the machine, illustrating the actuating mechanism for the stitch-forming mechanism and the drive for the rotary take-up member.

10 Fig. 5 is a view similar to Fig. 1, but with the take-up guard removed and the machine threaded, the needle being positioned at the upper end of its stroke.

15 Fig. 6 is an elevational view of the take-up guard with its cover swung open, exposing the opening through which the thread-ends can be removed in the event of thread breakage.

20 Figs. 7, 8, 9, 10, 11 and 12 are left-end elevations of the head of the machine with the take-up guard removed and showing the rotary hook diagrammatically, illustrating the position of the stitch-forming and thread-controlling elements at various points in the stitch-forming cycle.

Fig. 13 represents an enlarged front elevation of the take-up member, showing, when the thread breaks, the manner in which the thread winds on the take-up member and is thereby brought into the range of the thread-severing knife.

Fig. 14 represents a sectional view taken substantially along the line 14—14 of Fig. 13.

30 Fig. 15 represents an enlarged perspective view of the thread-severing knife.

Fig. 16 represents an enlarged fragmentary view of the thread-severing knife, showing the inclined sharpened edge against which the thread is pulled when abnormal winding occurs.

Fig. 17 represents an enlarged perspective view of the take-up member per se.

Fig. 18 represents the shape of the sheet metal stamping from which the take-up member shown in Fig. 17 is made.

Fig. 19 represents a vertical longitudinal sectional view of a lock-stitch vertical axis hook machine fitted with our improved rotary take-up.

45 Fig. 20 is an enlarged view partly in elevation and partly in section of the head end of the machine shown in Fig. 19.

Fig. 21 represents a front elevational view, with a portion of the arm in section, of a zigzag lock-stitch sewing machine equipped with a modified form of the improved rotary take-up.

50 Fig. 22 is an enlarged view partly in elevation and partly in section of the head end of the machine shown in Fig. 21.

Fig. 23 represents a top plan view of the take-up member taken along the line 23—23 of Fig. 22.

In the selected embodiment of the invention, the sewing machine illustrated has a frame including a bed 25 from which rises a standard 26 of a bracket-arm 27 terminating in an overhanging head 28. Journaled for endwise reciprocation in the head 28 is a needle-bar 29 carrying at its lower end a thread-carrying needle 30. The needle-bar 29 is reciprocated by means comprising a stud 31 (Figs. 1 and 4) clamped at one end to the needle-bar and embraced by the lower end of a needle-bar actuating link 32 connected at its upper end to a needle-bar actuating crank-pin 33 secured in a counter-balanced crank 34 mounted on the end of a rotary arm-shaft 35 journaled in the bracket-arm 27.

Cooperating with the needle 30, in the formation of lock-stitches, is a loop-taker 36 of the horizontal-axis rotary hook type and, as usual, performing a plurality of rotations for each reciprocation of the needle 30. The loop-taker 36 is carried on the outer end of a hook-shaft 37 to the inner end of which is secured a spur-gear 38 meshing with a second spur-gear 39 secured on a rotary bed-shaft 40 operatively connected in any suitable belt 40' to said arm-shaft 35. It will be understood that the arm-shaft 35, through the belt 40', will drive the bed-shaft 40 in the same direction as the arm-shaft rotates, and that the 2-to-1 ratio between the needle reciprocation and the hook 36 is obtained by the difference in size of the spur gears 38 and 39.

The work W is adapted to be advanced past the stitch-forming mechanism by a feed-dog 41 of the drop-feed type, the feed-dog 41 being carried by a feed-bar 42 pivotally connected at its rearward end to a feed-rocker 43 actuated in any suitable manner to impart work-advancing and -return movements to the feed-dog 41. At its forward end, the feed-bar 42 is formed with a depending fork 44 embracing a slide-block carried on the free end of a rock-lever 45 operated in any suitable manner to impart rising and falling movements to the feed-dog 41. Opposed to the feed-dog 41 is a presser-foot 46 secured to the lower end of the usual spring-depressed presser-bar 47 which is vertically movable in the bracket-arm head 28.

In the embodiment shown, our improved take-up comprises a single member, indicated generally as 48, having a body-portion 49 which is fixed by screws 50 to a disk 51 secured for limited circular adjustment by the center screw 52 and the clamping-screw 53 and slot 54 to the enlarged end 55 of the needle-bar actuating crank-pin 33. Closing the head of the machine is a flat plate 56 (Figs. 1 and 4) centrally apertured to provide clearance for the rotating disk 51. Interposed between the outer face of the disk 51 and the body-portion 49 of the take-up member is a spacer 57 the purpose of which is to provide a needle-thread passageway 58 between the flat plate 56 and the take-up member 48. The take-up member 48 is fixed to the crank-pin 33 so that the center of rotation of the take-up member coincides with the center of the arm-shaft 35 and, therefore, the take-up member 48 and the shaft 35 rotate in a clockwise direction about a common axis and at a uniform angular velocity.

As will be seen in Figs. 17 and 18, the take-up member 48 is preferably made of a single stamping blanked from sheet-metal and then bent into appropriate shape. The body-portion 49 of the take-up member 48 is drilled and countersunk at 59 to receive the securing screws 50. Extending in a direction radially outwardly from

the body-portion 49 is a spoke-like projection composed preferably of a pair of arms 60 and 61 which adjacent their free ends are bent or offset backwardly out of the plane of the back face 64 (Fig. 14) of the body-portion 49, as indicated at 62 and 63, and which arms at their free ends terminate in a bridge-piece 65 bent outwardly at substantially a right angle to the plane of said back-face 64. Projecting from the leading end of the bridge-piece 65 and bent back into substantial parallelism with and spaced from the body-portion 49 is a curved thread-confining finger 66, and extending from the trailing end of the bridge-piece 65 is a thread-confining tail 61. To effect an accurate control on the needle-thread during certain portions of the stitch-forming cycle, the arm 60 is formed with a curved elongated outer thread-engaging or controlling edge 69, effective during the taking up or stitch-tightening operation of the take-up, and the arm 61 is formed with an elongated outer thread-engaging or controlling edge 70, effective during the giving up or thread-slackening operation of the take-up. The opening 71 intermediate the two arms 60 and 61 is provided to reduce the weight of the rotating take-up member and thereby minimize the inertia effect set up by said rapidly rotating take-up member. As will be observed in Fig. 17, the outer thread-engaging edge 69 of the arm 60 merges with the bridge-piece 65 to form a throat 72 and, at its other end, blends into a flat finger-like guard 73 which functions to prevent the needle-thread-loop from flying off the take-up member immediately after the position of maximum take-up is passed. It will be seen in Fig. 13 also that the outer thread-engaging edge 70 of the arm 61 forms with the body-portion 49 of the take-up member a thread-notch 74, and that the body-portion 49 at its pointed extremity 75 is bent inwardly and buried in an aperture 76 formed in the disk 51, whereby the thread-passageway 58 between the take-up member 48 and the end-plate 56 is spanned and the thread-loop is transferred from the back to the front of the take-up member during the rotation thereof, as will hereinafter be more fully described. The take-up or stitch-tightening controlling edge 69 and the thread-slackening controlling edge 70 are disposed on opposite sides of the axis of rotation of the take-up and, at their narrowest point, the edges 69 and 70 are spaced apart a distance equal to at least one-half of the radial distance the throat 72 is spaced from the axis of rotation of the take-up, which, in the present case, is the longitudinal axis of the arm-shaft 35. This arrangement of the two thread-controlling edges has been found desirable from the point of view of accurate thread control. The spacing of the thread-controlling edges renders the take-up capable of exercising a good control of the thread and particularly so immediately following cast-off of the needle-loop. By properly shaping the thread-controlling edges of the take-up, a relatively early stitch-setting time is obtained, and following this early stitch-setting time the needle-thread is quickly relieved of its tension, thus making surplus or slack thread available for whatever tacking the operator may wish to perform. As may be seen in Fig. 11, the thread-controlling edge 69 is arcuate and extends from the take-up throat 72 inwardly in the general direction of the axis of rotation of the take-up element and at stitch-setting time is disposed so that, as shown in Fig. 11, the summation of the lengths of needle-thread from the thread-guide

83 to the thread-controlling edge 69 and from the thread-eye 85 to the thread-controlling edge 69 is constant at any point along the thread-controlling edge 69. The advantage of this arrangement of the controlling edge 69 is that at the critical stitch-setting time, the needle-thread-loop can be in engagement with the edge 69 anywhere along its length without requiring more or less thread than would be needed if the needle-thread-loop were located in the take-up throat 72. The flexibility thus obtained renders the take-up less critical in that the stitch is properly set whether or not the thread is located in the take-up throat 72.

It will be appreciated from the foregoing that the take-up member 48 rotates in a clockwise direction, and, that to facilitate threading, the take-up member is disposed outside of the flat end-plate 56. To protect the operator against injury by the rapidly rotating take-up member 48, there is provided a cup-shaped guard 76 supported at its lower end on an upstanding bracket 77 detachably secured to the machine-head 28. The open front face of the guard 76 is adapted to be closed by a swing-out cover 78.

Operation

The lead of the needle-thread T is from the source of supply to a thread-guide 79, thread-tension 80, check-spring 81, thread-guides 82 and 83, through the thread-passageway and over the take-up member 48, thread-guides 84 and 85 and thence to the needle 30. Assuming the parts to be in the position shown in Fig. 7, the needle 30 at this point in the stitch-forming cycle is in its lowest position and the needle-thread T passes upwardly from the thread-guide 83 between the guard-finger 73 and the thread-controlling edge 69 of the arm 60, then behind the arms 60 and 61, over the thread-controlling edge 70 of the arm 61 substantially at the thread-notch 74, and thence downwardly across the front face of the take-up member behind the thread-confining finger 66 to the needle 30. It will be seen in this figure that the thread-confining finger 66 is preferably made long so that its free end-portion will extend beyond or to the left of the limb of the needle-thread-loop leading from the take-up to the eye of the needle and thereby pass in front of the needle limb of the thread-loop before the thread-loop becomes too slack, thus precluding the possibility of the thread passing in front of the finger 66 and unthreading the take-up. It will be appreciated that the finger 66 should be quite long to take care of any excessive slack in the needle-thread which might be present as a result of a skipped stitch. When the machine is operated, the arm-shaft and hence the take-up member rotate in a clockwise direction at uniform angular velocity, while the hook 36 rotates in a counterclockwise direction at the usual 2-to-1 ratio.

In Fig. 8 the parts are shown in a position after the arm-shaft 35 has turned through the first few degrees, the needle having cast out its thread-loop and the beak of the hook 36 having just seized the same. In this position, the needle-thread T is shown sliding down or outwardly along the thread-controlling edge 70 of the arm 61 which is dropping bodily downwardly to give up the required slack thread needed to satisfy the hook requirements. It will be appreciated that the contour of the thread-controlling edge 70 lengthwise of the arm 61 is important and that it

is shaped so that a desired nicety of control is effected on the thread.

Fig. 9 discloses the position of the parts further along in the needle-loop expanding cycle. It will be observed that the take-up arms 60 and 61 have lowered to a position in which the needle thread T is quite slack, the thread-confining finger 66 and the tail 67 on the opposite ends of the bridge-piece 65 functioning to prevent the needle-loop from falling off the take-up member.

In Fig. 10 the parts are shown at the point in the stitch-forming cycle just prior to the time when the needle-loop is cast off the loop-taker 36. It will be seen by comparison of Figs. 8 and 9 that the take-up member has moved to the point where the needle-thread T is taut and immediately following cast off will start its thread take-up action. As a result of the tautness of the thread T, the same is drawn into the throat 72 at the junction of the thread-controlling edge 69 on the arm 60 and the thread-confining finger 66. The throat 72 is located at a point close to the periphery of the take-up member so that while the thread T is located in the throat, rotation of the take-up member effects its greatest take-up action on the thread.

Fig. 5 illustrates the next important position in the stitch-forming cycle. The needle-thread-loop has been cast off the loop-taker 36 and is being drawn up towards stitch-setting position. The needle 30 is at its upper end of the stroke. It will be observed that the needle-thread T is looped around the take-up arm 60 at the throat 72, the thread take-up action at this point being very rapid.

In Fig. 11, the stitch-setting position of the parts is shown. The take-up member in this position has reached the point of maximum take-up with the thread T still looped over the take-up arm 60 and in the throat 72. It will be seen that the thread lead to and from the take-up is in substantially straight lines, thus rendering the action of the take-up on the thread gentle and without any harsh jerks or pulls at stitch-setting time. It will be appreciated also that the offset portion 62 adjacent the outer end of the arm 60 functions to assist in retaining the needle-thread in the throat 72 for a slightly longer period than it would if the offset were not present. The advantage of retaining the needle-thread-loop in the throat 72 is the more uniform setting of a tight stitch.

Fig. 12 discloses the needle 30 just before it enters the work W on its next work-penetrating stroke. The thread T, which is looped over the thread-controlling edge 69 of the arm 60, travels sidewise slowly lengthwise of the thread-controlling edge 69 in response to the turning of the thread take-up member and to the recovery of the check-spring 81. The thread T is thus maintained under light tension until just before the needle 30 penetrated the work. This is advantageous because the limb of needle-thread leading from the take-up to the work cannot drop down before the descending point of the needle and be fouled thereby. Immediately upon the needle point entering the work sufficient slack is given to the thread as is needed by the needle to complete its penetration. The stitching cycle is then repeated beginning with the parts in the position shown in Fig. 7.

In rotary take-ups there is the problem of thread-winding in the event of accidental thread-breakage. To prevent the thread from being

wound about and hopelessly entangled in the operating parts of the take-up, there is provided a thread-severing device preferably comprising a stationary knife 86 (Figs. 15 and 16) having an inclined sharpened edge 87, the knife being formed integral with a cylindrical locating-portion or body 88 provided at one end of a shank 89 apertured at 90 to receive a suitable fastening screw 91 threaded into the flat end-plate 56. As clearly illustrated in Fig. 14, the flat end-plate 56 is formed with a hole 92 seized to snugly receive the cylindrical locating-portion 88 of the thread-cutter, the knife 86 extending into the thread-passageway 58 between the take-up member and the end-plate 56 with the shank 89 of the thread-cutter clamped against the back face of the end-plate by the fastening screw 91. Although the knife 86 projects into the thread-passageway 58, the loop of needle-thread about the take-up member is so handled by the latter during normal sewing that the limb of needle-thread in the thread passageway 58 is maintained below the range of the sharpened edge 87 of the cutter. This is clearly indicated in a comparison of Figs. 11 and 12, where it will be readily seen that the needle-thread T as it slides sidewise down the thread-controlling edge 69 of the arm 60 moves below the cutting edge of the knife 86 and, therefore, is not severed thereby. In the event of thread breakage, the thread T winds about the two take-up arms 60 and 61 adjacent the outer ends thereof between the offsets 62 and 63 and the bridge-piece 65, as shown, for example, in Figs. 13 and 14. When the needle-thread T is wound about the take-up member near the bridge-piece 65 the rear limb of the needle-thread is brought into the range of the thread-cutter 86 and severed thereby. The offsets 62 and 63 are important in that the portions of the arms 60 and 61 outwardly from these offsets are located rearwardly of the plane of the rear face 64 of the take-up body-portion 49 (Fig. 14). Thus when the needle-thread is wound about the arms 60 and 61, the lead of the rearward limb of the needle-thread-loop from the arm 60 to the notch 74 is displaced backwardly and across the cutting edge 87 of the thread-cutter 86. From the above, it will be appreciated that after thread breakage occurs the lead of the rearward limb of the needle-thread-loop on the take-up changes from a normal position below the range of the stationary thread-cutter to an abnormal position across the cutter. When in the abnormal position the thread is unerringly cut by the knife 86. When the thread is cut, the thread-end left around the take-up arms 60 and 61 is readily removed by swinging open the guard cover 78, permitting the thread-end to be grasped and pulled off the take-up. If the thread-end should be entangled to the point where it cannot be easily extracted, the opening 11 between the take-up arms 60 and 61 permits the insertion of a scissors or knife to cut the few strands of thread off the take-up.

From the foregoing, it will be understood that we have provided a single rotary take-up element for lock-stitch machines, which element can be readily blanked from sheet-metal accurately as to contour, after which the blank can be bent into proper form and rumpled to remove the sharp edges. Thus, the take-up element can be precisely reproduced at an extremely reasonable cost. As will be seen in Figs. 7 to 12, inclusive, the arms 60 and 61 provide a section extending outwardly from and in the plane of the body-

section 49, the opposite edges of which arms comprise the thread-engaging and -controlling edges 69 and 70 which are disposed on opposite sides of the center of rotation of the arm-shaft 35. From these figures, it will also be seen that the needle-thread-loop slides sidewise inwardly toward the center of rotation of the take-up element during the thread-slackening operation and outwardly away from the center during the stitch-setting or tightening operation. The provision of these two thread-controlling edges 69 and 70 has an additional advantage in that in the field the thread-controlling edges can be readily altered, as by filing, to accommodate special cases of thread handling. The thread-controlling edges 69 and 70 lend themselves to very precise formation, whereby a good control of the needle-thread is obtained during the entire stitch-forming cycle.

The sewing machine disclosed in Figs. 1 to 19, inclusive, is one in which the loop-taker 36 is journaled to rotate on a horizontal axis perpendicular to the vertical plane containing the line of feed. This type of machine is particularly well adapted to sew cloth fabrics of all types. In the leather industry, sewing machines are used extensively, and in sewing leather it is desirable to use a sewing machine having a needle-thread take-up which is capable of setting a uniformly tight stitch. It has been found that the present improved take-up satisfies this requirement to a nice degree. Figs. 19 and 20 disclose a machine of the type used in leather stitching which has been equipped with the improved single rotary take-up element 48. In this machine, the head 28 has journaled in it for endwise reciprocation a needle-bar 93 carrying at its lower end a thread-carrying needle 94 and at its upper end connected by a needle-bar actuating link 95 to a counterbalanced crank 96 carried on the front end of a rotary arm-shaft 97 journaled in the bracket-arm 27. Cooperating with needle 94 in forming lock-stitches is a rotary hook 98 carried on the upper end of a vertically arranged hook-shaft 99 journaled in a suitable saddle 100. The axis of the hook-shaft 99 is disposed normal to the upper plane of the work-support or bed 25. The hook-shaft 99 is rotated through the meshing gears 101 and 102, which have a ratio of 2-to-1, from a bed-shaft 103 which is belted, as at 104, to the arm-shaft 97. The work W is adapted to be advanced past the stitching mechanism by a feed-dog 105 actuated by any suitable feeding mechanism. The work W is yieldingly held in contact with the feed-dog 105 by a roller presser 106 carried on the lower end of a spring-pressed presser-bar 107 endwise slidable in the machine-head 28.

As will be observed in Fig. 19, the take-up element 48 is mounted on an extension of the needle-bar actuating crank 96 in a manner identical with that previously described in connection with the machine illustrated in Figs. 1 to 19, inclusive. The take-up element per se is substantially the same also, except for slight changes in the contour of the thread-controlling edges 69 and 70, and for this reason the same reference characters are used to identify similar parts in the take-up of both machines. It will be noted, however, that the direction of rotation of the take-up element is counterclockwise in the vertical axis hook machine (Figs. 19 and 20) and clockwise in the horizontal axis hook machine. In addition, it will be seen in Fig. 20 that the tension device 80 is secured to an extension 108

formed on the flat plate 56. Also the thread-guide 83 is adapted to be attached to the vertically yielding presser-bar 107 so that more or less needle-thread is allotted depending upon the thickness of the work traversed.

Another type of sewing machine in which the present needle-thread take-up has been embodied is shown in Figs. 21 and 22. This machine is a lock-stitch zigzag machine in which the needle is vibrated laterally across the seam line and the cooperating loop-taker is journaled on a horizontal shaft which is disposed so that the loop-seizing beak of the loop-taker rotates in a plane transversely of the line of feed. Referring to Fig. 21, it will be seen that the needle-bar 109 carrying at its lower end a needle 110 is journaled for endwise reciprocation in a vibratory frame 111 pivoted substantially at its midpoint to the head 28 of the machine. The upper end of the vibratory frame 111 is connected by a pitman 112 to a suitable adjustable eccentric 113 driven by reduction gearing from the rotary arm-shaft 114. Reciprocatory movements are imparted to the needle-bar 109 by means of a link 115 connected at its upper end to a needle-bar actuating crank 116 secured on the front end of the rotary arm-shaft 114. Cooperating with the needle 110 in the formation of lock-stitches is a loop-taker 117 of the rotary hook type which is carried on one end of a horizontally disposed hook-shaft 118 journaled in a saddle 119 so that the longitudinal axis of the hook-shaft is arranged parallel to the line of feed. The hook-shaft 118 has fixed on it a gear 120 in mesh with a gear 121 twice its size carried on a rotary bed-shaft 122 driven by a belt 123 from the arm-shaft 114. Through the mechanism just described, it will be appreciated that the hook 117 rotates twice for each reciprocation of the needle.

Like the other machines disclosed in the drawings, the rotary take-up element 48 of the zigzag machine is mounted on the extension of the needle-bar actuating crank 116 and rotates about an axis coincident with that of the arm-shaft 114. The take-up element for the zigzag machine is similar to that used on the two straight-away stitching machines hereinbefore described, excepting that the finger and tail projections which function to preclude accidental unthreading of the take-up are formed as a continuous thread-guarding loop 124 (Fig. 22), the central aperture 125 of which provides a clearance opening through which access may be had to any severed thread-loops which may be entangled on said take-up following thread breakage. As will be observed in Figs. 22 and 23, the thread-guarding loop 124 is provided on the take-up element beyond that portion on which the thread operates, and is formed by folding or bending back the extended loop into spaced parallelism with the thread-engaging portion of the take-up. It will be further seen that the loop 124 is extended to a point located on the opposite side of the axis of rotation of the take-up to that of the thread-engaging portion and that this extended portion is enlarged, preferably widthwise as at 126, to provide a weight mass for counterbalancing the rotary take-up element. The thread-controlling portions of the take-up element are substantially the same as those of the previously described take-up elements and therefore like reference characters have been applied to those portions.

It will be obvious that by forming the thread-guard as a closed loop 124, the possibility of in-

jury to the operation is minimized by the elimination of the pointed finger and tail projections. To further protect the operator against injury by the rotary take-up element, there is provided the stationary guard 127 which is fixed by screws 128 (Fig. 21) to a supporting bracket 129 fast on the machine head 28.

From the foregoing it will be apparent that the present invention contemplates an exceedingly simple form of rotary take-up element which effects a very nice control of the needle-thread during the entire cycle of operation of the take-up. With the take-up element formed as illustrated in the drawings, an accurate control is maintained on the needle-thread-loop during the initial expansion of the needle-thread-loop immediately following seizure of the loop by the loop-taker beak. Immediately following cast-off, the needle-thread-loop is taken up and at a sufficiently rapid rate such that the expanded loop is caused to slip off the beak without delay. By the use of the herein described take-up, it has also been possible to advance the stitch-setting point and thereafter give up thread quickly to provide slack thread to be used, if necessary, in tacking.

While an illustrative form of the invention has been described in considerable detail, it will be understood that numerous changes in the construction and arrangement of the parts may be made, without departing from its principles and scope as defined by the accompanying claims.

Having thus set forth the nature of the invention, what we claim herein is:

1. A sewing machine having in combination, a thread-carrying needle, means for reciprocating said needle, a rotary hook cooperating with said needle to form lock-stitches, means for rotating said hook at a uniform angular velocity twice for each reciprocation of said needle to cause it to seize loops cast out by said needle and pass the seized needle-loop around a lower thread mass, and a needle-thread take-up and slack thread controlling mechanism coordinated with said needle and rotary hook, said mechanism comprising a single rotary element operable about a fixed axis and having an elongated thread-engaging and -controlling portion which is arranged substantially normal to the plane of rotation of said element, means for directing the needle-thread transversely across the plane of rotation of said single rotary element, and means for imparting a complete revolution at a uniform angular velocity to said rotary take-up element once for each needle reciprocation.

2. A sewing machine having in combination, a thread-carrying needle, means for reciprocating said needle, a rotary hook cooperating with said needle to form lock-stitches, means for rotating said hook at a uniform angular velocity twice for each reciprocation of said needle to cause it to seize loops cast out by said needle and pass the seized needle-loop around a lower thread mass, and a needle-thread take-up and slack thread controlling mechanism coordinated with said needle and rotary hook, said mechanism comprising a single rotary element operable about a fixed axis and having an elongated thread-engaging and -controlling surface of varying radius from the axis of rotation of said element, thread-guides for directing the needle-thread transversely across the plane of rotation of said single rotary element, and means for imparting a complete revolution at uniform angular

velocity to said rotary take-up element once for each needle reciprocation.

3. A sewing machine having in combination, a thread-carrying needle, means for reciprocating said needle, a rotary hook cooperating with said needle to form lock-stitches, means for rotating said hook at a uniform angular velocity twice for each reciprocation of said needle to cause it to seize loops cast out by said needle and pass the seized needle-loop around a lower thread mass, and a needle-thread take-up and slack thread controlling mechanism coordinated with said needle and rotary hook, said mechanism comprising a single rotary element operable about a fixed axis and having a needle-thread take-up throat located adjacent its periphery and an elongated thread-engaging and -controlling edge extending from said throat inwardly toward said axis, and means for imparting a complete revolution at a uniform angular velocity to said rotary take-up element once for each needle reciprocation.

4. A sewing machine having in combination, a thread-carrying needle, means for reciprocating said needle, a rotary hook cooperating with said needle to form lock-stitches, means for rotating said hook at a uniform angular velocity a plurality of times for each reciprocation of said needle to cause it to seize loops cast out by said needle and pass the seized needle-loop around a lower thread mass, a needle-thread take-up and slack thread controlling mechanism coordinated with said needle and rotary hook, a pair of thread-guides below said take-up mechanism for guiding the thread in its travel to and from said take-up mechanism, said take-up and slack thread controlling mechanism comprising a single rotary element operable about a fixed axis and having a needle-thread take-up throat located adjacent its periphery and an elongated arcuate thread-engaging and -controlling edge extending from said throat inwardly toward said axis in a position at stitch setting time such that the summation of the lengths of thread measured from said edge to said thread-guides is constant for any point on said edge, and means for imparting a complete revolution at a uniform angular velocity to said rotary take-up element once for each needle reciprocation.

5. A sewing machine having in combination, a thread-carrying needle, means for reciprocating said needle, a rotary hook cooperating with said needle to form lock-stitches, means for rotating said hook at a uniform angular velocity a plurality of times for each reciprocation of said needle to cause it to seize loops cast out by said needle and pass the seized needle-loop around a lower thread mass, a needle-thread take-up and slack thread controlling mechanism coordinated with said needle and rotary hook, a pair of thread-guides below said take-up mechanism for guiding the thread in its travel from said take-up mechanism to said needle, said take-up and slack thread controlling mechanism comprising a single rotary element operable about a fixed axis and having a needle-thread take-up throat located adjacent its periphery and an elongated arcuate thread-engaging and -controlling edge extending from said throat circularly about said axis at a radius such that the needle-thread-loop dimension between the thread-guides and over said arcuate edge is constant over substantially the entire length of said edge at stitch-setting position of said take-up element, and means for imparting a complete revolution at a uniform

angular velocity to said rotary take-up element once for each needle reciprocation.

6. A sewing machine having in combination, a thread-carrying needle, means for reciprocating said needle, a rotary hook cooperating with said needle to form lock-stitches, means for rotating said hook at a uniform angular velocity twice for each reciprocation of said needle to cause it to seize loops cast out by said needle and pass the seized needle-loop around a lower thread mass, and a needle-thread take-up and slack thread controlling mechanism coordinated with said needle and rotary hook, said mechanism comprising a single rotary flat spoke-like member having opposed edges of which one has a needle-thread take-up thread-engaging and -controlling portion and the other edge has a slack thread controlling portion, and means for imparting a complete revolution at a uniform angular velocity to said spoke-like member once for each needle reciprocation.

7. In a sewing machine, a thread-carrying needle, means for reciprocating the same, a rotary loop-taker operated at twice the frequency of said needle and arranged to cooperate with said needle-thread, take-up means for said needle-thread comprising a single rotary member having opposed thread-engaging surfaces of varying radius from the center of said member and rotatable in a zone substantially normal to the axis of rotation of said member for providing a camming action on the thread, thread guiding means for directing the needle-thread through the zone of action of said thread-engaging surfaces, and means for rotating said single rotary member at uniform angular velocity at the frequency of needle reciprocation.

8. In a sewing machine having a reciprocatory thread-carrying needle and a rotary loop-taker coordinated therewith and making two revolutions for each reciprocation of said needle, a rotary take-up mechanism of which the take-up member comprises solely a single rotary element operating about a fixed axis and having a thread-engaging surface of varying radius from the axis of rotation of said element for acting on the needle-thread during each stitch-forming cycle, and means for rotating said single take-up member at uniform angular velocity about said fixed axis.

9. In a sewing machine having a reciprocatory thread-carrying needle and a rotary loop-taker coordinated therewith in the formation of lock-stitches, a needle-thread take-up mechanism of which the take-up member comprises a single rotary element having a thread-engaging surface of varying radius from the axis of rotation of said element for acting on the needle-thread during each stitch forming cycle, a needle-actuating rotary shaft, means for securing said single rotary element to said needle-actuating shaft and having capacity providing for adjustment of said take-up element about the axis of said shaft, a rotary shaft carrying said loop-taker, and connections between said two rotary shafts for operating said loop-taker carrying shaft at a speed exceeding that of said needle-actuating shaft.

10. In a sewing machine having a reciprocatory thread-carrying needle and a rotary loop-taker coordinated therewith in the formation of lock-stitches, a rotary needle-actuating shaft, a rotary loop-taker actuating shaft operatively connected to rotate at a different speed than that of said needle-actuating shaft, a rotary needle-thread take-up mechanism of which the rotary

member is rotatable about a fixed axis, and mounting means for said rotary member including a disk having a slot and a clamping screw extending through said slot.

11. In a sewing machine having a reciprocating thread-carrying needle and a rotary loop-taker coordinated therewith and making a plurality of revolutions for each reciprocation of said needle, a rotary take-up mechanism of which the take-up member comprises solely a single rotary element operating about a fixed axis and on which the loop of needle-thread slides sidewise inwardly toward and outwardly away from said fixed axis for the thread-slackening and stitch-tightening operations, and means for rotating said single take-up member at uniform angular velocity about said fixed axis.

12. In a sewing machine having a reciprocating thread-carrying needle and a rotary loop-taker coordinated therewith and making a plurality of revolutions for each reciprocation of said needle, a single rotary take-up member rotatable about an axis and on which take-up member the loop of needle-thread slides sidewise inwardly toward and outwardly away from said axis for the thread-slackening and stitch-tightening operations, and means for rotating said single take-up member at uniform angular velocity about said axis.

13. In a sewing machine having a reciprocating thread-carrying needle and a rotary-loop-taker coordinated therewith in the production of lock-stitches, a rotary take-up mechanism of which the rotary member comprises a unitary plate-like element rotatable about an axis and having spaced thread-controlling edges extending longitudinally of said element outwardly from its center and arranged on opposite sides of the axis of rotation of said element and adapted to act individually on said thread during different portions of the stitch-forming cycle, and means for rotating said take-up member about its axis.

14. A rotary take-up member for a lock-stitch sewing machine having a reciprocating needle and a circularly moving loop-taker, comprising, a body-portion, a thread-engaging section extending outwardly from said body-portion and provided with opposed thread-controlling edges on which the needle-thread is adapted to slide in and out of the length of the section during different portions of each stitch-forming cycle, and oppositely disposed finger and tail sections formed on the free end of said outwardly extending section providing for precluding accidental unthreading of the take-up during operation thereof.

15. A rotary take-up member for a lock-stitch sewing machine having a reciprocating needle and a circularly moving loop-taker, comprising, a body-portion, a thread-engaging section extending outwardly from said body-portion and provided with opposed thread-controlling edges on which the needle-thread is adapted to slide in and out of the length of the section during different portions of each stitch-forming cycle, and oppositely disposed finger and tail sections projecting from the free end of said outwardly extending section and folded back into spaced parallelism with the body-portion of said take-up member, thereby to prevent the needle-thread-loop from accidentally falling off the take-up during the operation thereof.

16. A sewing machine having in combination, a thread-carrying needle, means for reciprocating

ing said needle, a rotary hook cooperating with said needle to form lock-stitches, means for rotating said hook at a uniform angular velocity twice for each reciprocation of said needle to cause it to seize loops cast out by said needle and pass the seized needle-loop around a lower thread mass, and a needle-thread take-up and slack thread controlling mechanism coordinated with said needle and rotary hook, said mechanism comprising a single plate-like element rotatable about an axis and having a thread-engaging section extending outwardly from the axis of rotation of said element providing thread-controlling edges on which the needle-thread is adapted to slide in and out of the length of the section during different portions of each stitch-forming cycle, and a thread-confining finger formed on the free end of said outwardly extending thread-engaging section and folded back into spaced relation with said section, said finger having its free end terminating at a point beyond the limb of the needle-thread-loop leading from the take-up to the needle at the loop-seizing point in the stitch-forming cycle.

17. In a sewing machine, a thread-carrying needle, means for reciprocating the same, a rotary loop-taker operated at twice the frequency of said needle and arranged to cooperate with said needle-thread, a rotary take-up mechanism of which the rotary member comprises a single plate-like element rotatable about an axis and having a thread-receiving throat and spaced opposed thread-engaging edges each of varying radius from the center of said element, said thread-engaging edges being spaced apart a distance equal to at least one-half the radial distance of said thread-receiving throat from said center of rotation of said take-up member.

18. In a sewing machine having a reciprocating thread-carrying needle and a rotary loop-taker coordinated therewith and making a plurality of revolutions for each reciprocation of said needle, a rotary take-up mechanism of which the rotary member comprises solely a single flat plate-like element rotatable about an axis and having a needle-thread take-up thread-controlling portion and a slack thread-controlling portion, said plate-like element having a section near its periphery offset out of the plane of the major part of said element and about which the needle-thread winds in the event of thread-breakage, a thread-severing device disposed to sever the needle-thread when it winds about said offset section, and means for imparting revolutions at uniform angular velocity to said take-up element.

19. A rotary take-up member for a lock-stitch sewing machine having a reciprocating needle and a circularly moving loop-taker, comprising a flat plate-like body-portion provided with a thread-engaging section extending from said body-portion and affording opposed thread-controlling edges on which the needle-thread is adapted to slide in and out of the length of the section during different portions of each stitch-forming cycle, said section beyond the portion on which the thread operates being bent backwardly into spaced parallelism with said thread-engaging portion, and a weight mass provided on said bent back portion to balance said take-up member.

20. A rotary take-up member for a lock-stitch sewing machine having a reciprocating needle and a circularly moving loop-taker com-

prising a flat plate-like body-portion provided with a thread-engaging section extending from and in the plane of said body-portion and affording opposed thread-controlling edges on which the needle-thread is adapted to slide in and out of the length of the section during different portions of each stitch-forming cycle, said section beyond the portion on which the thread operates being bent backwardly into spaced parallelism with said thread-engaging portion thereby to provide means precluding accidental unthreading of the take-up member, said bent back portion being apertured to form clearance facilitating the removal of thread abnormally wound on the take-up member.

21. A sewing machine having in combination, a work-support, a thread-carrying needle, means for reciprocating said needle, work-feeding mechanism, a rotary hook cooperating with said needle to form lock-stitches and journaled to rotate about an axis normal to the upper surface of the work-support, means for rotating said hook at a uniform angular velocity twice for each reciprocation of said needle to cause it to seize loops cast out by said needle and pass the seized needle-loop around a lower thread mass, and a needle-thread take-up and slack thread controlling mechanism coordinated with said needle and rotary hook, said mechanism comprising a single rotary element operable about a fixed axis and having an elongated thread-engaging and -controlling surface of varying radius from the axis of rotation of said element, thread-guides for directing the needle-thread transversely across said surface, and means for imparting a complete 35

revolution at uniform angular velocity to said rotary take-up element once for each needle reciprocation.

22. A sewing machine having in combination, 5 a work-support, a thread-carrying needle, means for reciprocating said needle, work-feeding mechanism for advancing the work past said needle, a rotary loop-taker having a loop-seizing beak rotating in a plane transversely of the line of feed, means for rotating said loop-taker at a uniform angular velocity twice for each reciprocation of said needle, and a needle-thread take-up and slack thread controlling mechanism coordinated with said needle and loop-taker, said mechanism comprising a single rotary element operable about a fixed axis and having opposed elongated thread - engaging and -controlling edges each of varying radius from the axis of rotation of said element, thread-guides for directing the needle-thread transversely across said edges, and means for imparting a complete revolution at uniform angular velocity to said rotary take-up element once for each needle reciprocation.
